UNITED STATES PATENT OFFICE.

WILLIAM A. REAM, OF MORGANTOWN, WEST VIRGINIA.

DESIGN FOR A RUBBER HEEL.

57,150.

Specification for Design.

Patented Feb. 22, 1921.

Application filed February 3, 1920. Serial No. 355,985. Term of patent 14 years.

To all whom it may concern:

Be it known that I, WILLIAM A. REAM, a citizen of the United States, residing at Morgantown, in the county of Monongalia and the State of West Virginia, have invented a new, original, and ornamental Design for a Rubber Heel, of which the following is a specification, reference being had to the accompanying drawing, forming a part thereof.

Figure 1 is a face view of the under side of the heel, and

Fig. 2 is a transverse sectional view taken substantially on line 2—2 of Fig. 1.

What I claim is:

The ornamental design for a rubber heel, as shown in the drawing.

WILLIAM A. REAM.
